US0D1009082S

(12) **United States Design Patent** (10) **Patent No.:** **US D1,009,082 S**
(45) **Date of Patent:** **** Dec. 26, 2023**

(54) **METERING PUMP**

(71) **Applicant:** **ViscoTec Pumpen- u. Dosiertechnik GmbH**, Töging am Inn (DE)

(72) **Inventors:** **Raphael Lichtnecker**, Töging am Inn (DE); **Horst Kelsch**, Töging am Inn (DE); **Thomas Goeller**, Töging am Inn (DE)

(73) **Assignee:** **VISCOTEC PUMPEN- U. DOSIERTECHNIK GMBH**, Töging am Inn (DE)

(**) **Term:** **15 Years**

(21) **Appl. No.:** **35/515,275**

(22) **Filed:** **Mar. 29, 2022**

(80) **Hague Agreement Data**

Int. Filing Date: **Mar. 29, 2022**

Int. Reg. No.: **DM/219948**

Int. Reg. Date: **Mar. 29, 2022**

Int. Reg. Pub. Date: **Sep. 30, 2022**

(30) **Foreign Application Priority Data**

Sep. 30, 2021 (DE) 40 2021 100 900.0

Assistant Examiner — Mark T. Philipp

(74) **Attorney, Agent, or Firm:** Alleman Hall Creasman & Tuttle LLP

(57) **CLAIM**

The ornamental design for a metering pump, as shown and described.

DESCRIPTION

1. Metering pump

1.1 : Front

1.2 : Back

1.3 : Right

1.4 : Left

1.5 : Top

1.6 : Bottom

1.7 : Perspective

1.8 : Cross section through FIG. 1.1

(Continued)

The design of the metering pump in the reproductions is made from transparent or translucent material.

1 Claim, 8 Drawing Sheets
